UNITED STATES PATENT OFFICE.

ASHER R. SMITH, OF LAREDO, TEXAS.

WIRE GARDEN-HOSE SUPPORT.

Application filed October 20, 1921. Serial No. 509,011.

To all whom it may concern:

Be it known that I, ASHER R. SMITH, a citizen of the United States, residing at Laredo, in the county of Webb and State 5 of Texas, have invented certain new and useful Improvements in Wire Garden-Hose Supports; and I do declare the following to be a full, clear, and exact description of the invention, such as will enable others 10 skilled in the art to which it appertains to make and use the same.

This invention relates to an improved hose support by means of which a garden hose may be held and the water from the hose 15 directed upwardly so that a sprinkler will be provided. One object of the invention is to provide a hose supporter which can be formed from a single strand of heavy resilient wire bent to form upper and lower hose engag- 20 ing clamps and a twisted standard carrying the clamps and adapted to have its lower end portion embedded in the ground.

Another object of the invention is to so construct this supporter that the portions 25 of the wire which will form the clamps will be firmly braced and the arms thus yieldably held against outward movement and caused to firmly grip the hose.

Another object of the invention is to pro- 30 vide a garden hose support which will be cheap to produce and very effective in operation.

This invention is illustrated in the accompanying drawing, wherein:

35 Figure 1 is a view in front elevation showing a hose supported in an operative position by means of the improved hose supporter.

Figure 2 is a perspective view of the hose 40 supporter with the lower portion broken away.

This improved hose supporter is to be formed from a single strand of relatively heavy resilient wire. In forming the hose 45 supporter, the strand of wire will first be bent to form the upper clamp which is indicated in general by the numeral 1 in Fig. 1 and will then be twisted to form the staff portion 2 between the clamps. The wire 50 will then be bent to form the lower clamp which is indicated in general by the numeral 3 and will then be further twisted to form a continuation of the staff, the lower portion of this staff being formed of a single un-

twisted strand and forming a prong portion 4 which is to be embedded in the ground when it is desired to make use of the supporter. 55

After doubling the strand of wire and crossing the strand to provide the arm 5 of 60 the upper clamp, one of the strands formed by bending the length of wire will in its turn be bent and crossed as shown at 6 to form the second arm 7 of this upper clamp. The strand will then be carried be- 65

neath the inner end portion of the clamp as shown at 8 and the two strands will be twisted together to form the portion of the staff 2 between the upper and lower clamps. One of the strands will then be bent to form 70 the arms 9 and 10 of the lower clamp and the lower clamp will be turned so that the arms of the clamp extend horizontally beneath the arms of the clamp 1 and the end portion of this strand extends through an eye 75

11. The two strands will now be further twisted to form the lower portion of the staff. From an inspection of Fig. 1, it will be seen that when the length of wire is first doubled, it is to be doubled at such a point that one end portion or strand will be of greater length than the second end portion or strand and therefore when the end portions of the wire are twisted together beneath the lower clamp, one end portion 80 will terminate short of the end of the second end portion. This provides the prong 4 which is to be embedded in the ground. 85

When this garden hose support is in use, the hose 12 will be forced between the arms 90 of the two clamps with the nozzle 13 positioned above the upper clamp. The hose will be firmly gripped by the two clamps and will be held in the position shown in Fig. 1. The prong 4 will then be forced 95 into the ground and the hose will be held in an upright position. If it is desired to have the hose extend vertically, the supporter will be planted vertically in the ground but if it is desired to have the hose 100 extend at an incline, the prong 4 will of course be embedded in the ground with the supporter extending at the desired angle. By having the device formed from resilient wire, it can accommodate itself to different 105 sizes of hose, this being due to the fact that the arms may be bent closer together or farther apart as may be necessary in order

to grip a hose which is somewhat smaller or somewhat larger than the size for which the holder is intended.

I claim:

- 5 A garden hose supporter formed from a length of resilient wire doubled intermediate its length to form a two strand standard, each of the strands formed by the doubling of the wire being then doubled and bent to form the arms of a substantially U-shaped upper clamp, said clamp lying in a plane substantially at right angles to the standard and parallel to the ground, one of the strands being further doubled at a lower

point to form one arm or a substantially U-shaped lower clamp and further doubled and bent to form the second arm of the lower clamp, said lower clamp lying in a plane substantially at right angles to the standard and parallel to the ground, the lower clamp being then turned to provide an eye at the inner end of the lower clamp for receiving the strand and the strands being then twisted together to form the portion of the standard before the lower clamp.

In testimony whereof I have hereunto set my hand.

ASHER R. SMITH.
